(57) **CLAIM**

The ornamental design for a reef block, as shown and described.

DESCRIPTION

FIG. 1 is a first perspective view of a reef block;
FIG. 2 is a second perspective view thereof;
FIG. 3 is a front view thereof;
FIG. 4 is a back view thereof;
FIG. 5 is a first side view thereof;
FIG. 6 is a second side view thereof;
FIG. 7 is a top view thereof;
FIG. 8 is a bottom view thereof;
FIG. 9 is a cross-sectional view taken along line 9-9 in FIG. 7; and,
FIG. 10 is a cross-sectional view taken along line 10-10 in FIG. 7.
The broken lines in FIGS. 1 to 10 illustrate portions of the reef block that form no part of the claimed design.

1 Claim, 7 Drawing Sheets
